FIG. 1.

FIG. 2.

FIG. 3.

FIG. 4.

INVENTOR:

Robert Wilkinson Newton

By Chas. H. Luther

ATTORNEY:

UNITED STATES PATENT OFFICE.

ROBERT WILKINSON NEWTON, OF PROVIDENCE, RHODE ISLAND.

AUTOMATIC SPRINKLER.

1,392,593.

Specification of Letters Patent.

Patented Oct. 4, 1921.

Application filed April 29, 1920. Serial No. 377,620.

To all whom it may concern:

Be it known that I, ROBERT WILKINSON NEWTON, a citizen of the United States, residing at Providence, in the county of Providence and State of Rhode Island, have invented a new and useful Improvement in Automatic Sprinklers, of which the following is a specification.

My invention has reference to an improvement in automatic sprinklers and more particularly to an improvement in the valve support and releasing device of automatic sprinklers.

In automatic sprinklers, as heretofore constructed, the valve support and releasing device usually consists of a plurality of parts held together by solder. In case of a fire the solder melts and the parts of the valve support and releasing device disintegrate, thereby opening the valve and allowing the water to flow through the sprinkler. In practice it has been found impossible to produce a solder for this purpose, that will always melt at an exact predetermined temperature; consequently such automatic sprinklers, under fire conditions, will go off anywhere from fifty seconds to two minutes or more later than the time they are set to go off.

The object of my invention is to improve the construction and operation of automatic sprinklers, whereby such sprinklers will open or go off, under fire conditions, at an exact predetermined temperature.

My invention consists in the peculiar and novel construction and operation of an automatic sprinkler and more particularly in the construction and operation of a valve support and releasing device for automatic sprinklers, as will be more fully set forth hereinafter and claimed.

Figure 1 is a front view of my improved sprinkler.

Fig. 2 is a sectional view taken on line 2, 45 2 of Fig. 1.

Fig. 3 is an enlarged front view of the valve support and releasing device, and

Fig. 4 is a longitudinal sectional view through the valve support and releasing device and showing the electrical system and connections.

In the drawing 5 indicates an automatic sprinkler body and 6 my improved electrically operated valve support and releasing device.

The sprinkler body 5 has a screw-threaded

tubular shank 7, arms 8—8 curving to a hub 9, screw 10 screw-threaded through the hub 9 and deflector 11 on the hub. Guard bars 12—12 are secured at each end to, at each side of and extend lengthwise of the body 5, as shown in Figs. 1 and 2. A valve head 13 normally closes the valve seat 14, the valve head 13 having a central depression 15 and the screw 10 having a cone shaped inner end 16, as shown in Fig. 2.

My improved valve support and releasing device 6 consists of a tube 17 having a closed cone-shaped end 18, a screw-threaded end 19 closed by a screw-cap 20 having a depression 21 in its top for the cone-shaped inner end 16 of the screw 10.

In the tube 17 is an explosive substance 22 or an expandable substance and preferably a detonator 23. The tube 17 is preferably of glass and to this tube is formed integral therewith a glass indicating thermometer 24 having the usual column of mercury 26 and Fahrenheit scale 27. As the tube 17 and thermometer 24 are of glass, the indicating scale 27 may be used as a thermometer scale, as a scale by which the amount of explosive substance in the tube 17 may be accurately gaged, and also the expansion of the said explosive substance may be gaged by the scale. A wire 28 is electrically connected to the detonator 23, it extends through the cap 20 and is then connected to a source of electrical energy, as indicated at 29. A wire 30 extends from the source of electrical energy 29 to and through the thermometer 24 into the mercury 26, and a wire 31 is electrically connected to the detonator 23, and extends through the cap 20 and then down through the top of the thermometer 24 into the thermometer which now acts as an automatic electrical switch. The end 32 of the wire may extend down to any degree of temperature required, say 155 degrees Fahrenheit, as shown in Fig. 3. The end 18 of the tube 17 enters the depression 15 in the valve head 13 and the end 16 of the screw 10 enters the depression 21 in the cap 20. By tightening the screw 10 the valve head 13 is firmly secured in place.

When the sprinkler is in use under fire conditions and the heat of the fire has reached, say 155 degrees at the sprinkler, the end of the mercury 26, rising in the thermometer, will touch the end 32 of the wire 31, thereby closing the circuit. The explosive substance 22 will then instantly

explode, destroying the tube 17, releasing the valve head 13 and causing the sprinkler to open instantly at 155 degrees of temperature. By varying the position of the end 32 5 of the wire 31, in the thermometer, the sprinkler may be caused to open instantly at any degree of temperature desired.

Although I have shown and have the right to use a well known simple electric system 10 for operating my improved sprinkler, in the same way that such an electric system may be used for operating a burglar alarm, I do not claim the electric system *per se*.

It is evident that any form of a thermometer or expansive element could be used 15 on the sprinkler as an automatic switch, and details of construction could be varied to accomplish practically the same result; also the thermometer on the sprinkler is used for 20 testing in an oven, for the degree of heat required to operate the sprinkler.

Having thus described my invention I claim as new—

1. An automatic sprinkler having a holder 25 in the form of a strut of glass or other breakable material and interposed inter-

mediate the valve seat and the frame hub, said holder having scales to record the amount and expansion of the material in the holder. 30

2. An automatic sprinkler having a holder in the form of a hollow glass strut intermediate the valve seat and the frame hub, said holder having a recording scale, a thermometer scale and an indicating scale. 35

3. An automatic sprinkler having incorporated therein a thermometer forming one of the controlling elements of the sprinkler, for the purpose, as described.

4. The combination with an automatic 40 sprinkler of a thermometer in strut formation and interposed intermediate the valve seat and the frame hub of the sprinkler.

5. The combination with an automatic 45 sprinkler of a thermometer in strut formation and interposed between the valve head and the frame hub of the sprinkler and an electric attachment on the thermometer strut formation.

In testimony whereof, I have signed my 50 name to this specification.

ROBERT WILKINSON NEWTON.
